UNITED STATES PATENT OFFICE.

WILLIAM WILCOX AND WILLIAM ALARIC WILCOX, OF GRAND RAPIDS,
MICHIGAN.

EVAPORATOR.

SPECIFICATION forming part of Letters Patent No. 407,048, dated July 16, 1889.

Application filed March 19, 1889. Serial No. 303,852. (No model.)

To all whom it may concern:

Be it known that we, WILLIAM WILCOX and WILLIAM ALARIC WILCOX, citizens of the United States, residing at Grand Rapids, 5 in the county of Kent and State of Michigan, have invented certain new and useful Improvements in Evaporators; and we do hereby declare the following to be a full, clear, and exact description of the invention, such as 10 will enable others skilled in the art to which it appertains to make and use the same.

Our invention relates to evaporators, and has for its object improvements on the constructions shown in our application filed January 28, 1887, Serial No. 225,815.

The invention will be hereinafter described, and particularly pointed out in the claims.

In the accompanying drawings, which form part of this specification, Figure 1 represents 20 a plan view of our improved evaporator; Fig. 2, a vertical longitudinal section of the same; Fig. 3, a vertical transverse section, on an enlarged scale, on the line *x x*, Fig. 2; and Fig. 4, a perspective view of the heater detached.

Reference being had to the drawings and the letters thereon, A indicates an arch, the construction of which is described and claimed in the application to which reference has been made, except the features which co- 25

30 operate with our improved heater herewith shown. The arch is provided with an extension B at its rear end, which projects beyond the heater C when in position for heating sirup, as shown in Figs. 2 in full lines, and forms a support for the heater when it is drawn out of the uptake D, as shown by dotted lines in said figure. The uptake crosses the arch near the rear end and is secured thereto, and the sides *a b* and the front end *c* 35 thereof inclose the horizontal extension E of the heater and cause the gases of the combustible material in the furnace to pass through the vertical flues *d* in said extension and impart their heat to the juice surround- 40

45 ing the flues in the heater. The uptake is provided with a suitable chimney or stack (not shown) to carry off smoke and is open at its rear end, so that the heaters C may be withdrawn and a direct draft produced 50 through the uptake when the run or charge

of juice is being finished in the evaporating-pan. When the heater C is withdrawn from the uptake D, it rests upon the extension B of the arch, and the front end of the extension E forms the rear wall of the uptake, as shown 55 in dotted lines in Fig. 2, and presents sufficient surface to the heated gases passing on to the stack to keep the juice in the heater hot until it has all been worked through the evaporating-pan. The juice flows from a suit- 60 able tank into the heater and from the heater it flows through a pipe *e* into the receiving-compartment *f* of the evaporating-pan *F*, where the supply is regulated automatically by a valve *g*, controlled by a float *h*. 65

The automatic supply-valve is fully shown, described, and claimed in our application filed September 8, 1887, Serial No. 249,137.

The supply of juice from a tank to the heater may be controlled by a duplicate of the valve 70 shown in the receiving-compartment *f* by placing it in the heater.

In finishing a run or charge of juice, or at the close of the operation of evaporating, the juice in the vertical extension G of the heater 75 C below the level of the pipe *e*, where it connects with the heater, is withdrawn through a faucet *i* and poured into the compartment *f* of the evaporating-pan.

The boiling-compartment of the pan is des- 80 ignated by the letter *k* and the finishing-compartment by *l*. The latter compartment is provided with a transverse depression *m*, which is inclined toward the discharge side thereof and the valve *n* for the purpose of 85 drawing the sirup therefrom.

The juice flows from one compartment in the pan to another through suitable openings (not shown) in the vertical partitions *o, p, q*, and *r* from the receiving to the finishing com- 90 partment.

Having thus fully described our invention, what we claim is—

1. In an evaporator, the combination of an arch having an uptake provided with an open 95 end, and a removable heater having flues and projecting into the uptake, substantially as described.

2. In an evaporator, the combination of a removable heater provided with flues and an 100

arch having an open uptake and an extension to form a support for the heater when withdrawn from the uptake, substantially as described.

- 5 3. In an evaporator, an arch having an uptake supported thereon, one end of said uptake being open, in combination with a horizontally-sliding heater having a horizontal extension provided with a series of tubes and constructed to be inserted into the uptake through the open end, substantially as described.
- 10 4. In an evaporator, an arch having an uptake open at one end, in combination with a

removable heater having a horizontal extension provided with a series of vertical flues and a vertical extension in the rear thereof provided with a discharge-pipe near its upper end, and a valve for drawing off the contents below the discharge-pipe, substantially as described. 15

In testimony whereof we affix our signatures in presence of two witnesses.

WILLIAM WILCOX.

WILLIAM ALARIC WILCOX.
